UNITED STATES PATENT OFFICE.

EUGENE H. TAYLOR, OF LYNN, MASSACHUSETTS.

PAPER-BOX-MAKING MACHINE.

SPECIFICATION forming part of Letters Patent No. 541,953, dated July 2, 1895.

Application filed November 17, 1893. Serial No. 491,273. (No model.)

To all whom it may concern:

Be it known that I, EUGENE H. TAYLOR, of Lynn, county of Essex, State of Massachusetts, have invented an Improvement in Paper-Box-Making Machines, of which the following description, in connection with the accompanying drawings, is a specification, like letters and numerals on the drawings representing like parts.

10 This invention has for its object the production of a rapidly operating machine adjustable within very wide limits, for the manufacture of paper boxes and their covers, whereby the stock from which they are made, 15 whether heavy or light, may be acted upon with equal facility, and the finished article accurately and quickly produced.

In this machine, as will be hereinafter described, the blanks from which the boxes or 20 covers are to be made are placed in position between adjustable guides located above a tank containing wetting devices and pasting devices, the undermost blank of the pile of blanks being supported between its ends on 25 suitable tracks, the wetting devices rising at the proper time and wetting the said undermost blank transversely and longitudinally in the lines on which it is to be subsequently folded, to form the flanges or sides of the box 30 or cover, the width of the flanges depending on the depth of the box or cover to be made, while the pasting devices rise and apply paste to parts of the blank to be turned over, in order that other parts of the flanges may be 35 pasted to them, the wetting and pasting devices in their general construction and arrangement being substantially as shown and described in United States Patent No. 418,690, granted to George H. Cushman and myself.

40 January 7, 1890, particular features and differences thereover being hereinafter particularly described and claimed. The blanks of the pile are thereafter fed forward one by one from the bottom of the pile by a feeder along 45 supporting tracks into position between a former and a follower, both of which are suitably guided and made movable vertically with relation to said tracks or to the bed of the machine, and the wet and pasted blank is carried up by the former to the follower, and 50 caught and held between them, and the projecting portions of the blank are then sub-

jected to the action of lip turners, which positively turn the side and corner flaps of the blank over upon the former, after which the former rises with the blank, taking with it the follower, the former and follower together moving the blank held between them past side and end plates or wipers, the latter causing the end flaps of the blank to be wiped or 60 turned down upon the corner flaps, previously turned over and held upon the former by the lip turners.

As herein shown, the flanges or edges of the blank which are to constitute the sides of the 65 box or cover are first turned down by the lip turners, after which continued movement of the said turners folds them and turns the corner flaps snugly about the corners of the former, the lip turners remaining stationary 70 in such position and holding the side and corner flaps against the sides and ends of the former, until further vertical movement thereof causes the end flanges or flaps of the blank to be turned over upon the corner flaps. 75 When the end flanges or flaps have been thus turned down against the corner flaps the former has reached the limit of its upward movement, and it is arrested. The blank is then subjected to compressing mechanism to 80 complete the sides and ends of the box or cover, after which the former and follower and the lip turners return to their normal positions, and an ejector delivers the completed 85 box or cover from between the separated former and follower.

In accordance therewith my invention consists in the combination, with a former, of compound lip turners located at the corners thereof, and actuating means to automatically move said lip turners toward the sides of the former, a portion of the lip turners being made to turn at right angles to the other portion and about the corners of the former, whereby the sides and the corner flaps of a blank are 95 turned over upon the sides and ends of the former, substantially as will be described; also, in the combination, with a former, of compound lip turners located at the corners thereof, adjusting devices for the lip turners, 100 and actuating means to automatically move said lip turners toward the sides of the former, a portion of the lip turners being made to turn at right angles to the other portion and

about the corners of the former, whereby the sides and the corner flaps of a blank are turned over upon the sides and ends of the former, substantially as will be described; 5 also, in the combination, with a former, of folding lip turners located adjacent the corners thereof and normally extended in the same plane, and actuating means to move said lip turners simultaneously toward the sides of 10 the former, to turn the side flanges of a blank, and thereafter to automatically swing or fold portions of said lip turners around the corners and ends of the former, to thereby turn the corner flaps of the blank inward against 15 the ends of the former, substantially as will be described.

Other features of this invention will be hereinafter described and pointed out in the claims at the end of this specification.

- 20 20 Figure 1, in elevation, represents the upper portion of the delivery end of the machine embodying my invention, with the parts in position to receive the blank, the feeding mechanism having partly positioned it. Fig. 2, in elevation, represents the lower portion of the delivery end of the machine shown in Fig. 1, and, taken in connection therewith, shows the delivery end of the machine complete. Figs. 3 and 4, in elevation and taken together, show 25 30 the right-hand side of the machine. Fig. 5 is a vertical longitudinal sectional view taken on the line $x-x$, Fig. 1. Fig. 5^a is a perspective detail of the adjustable presser feet, to be described. Fig. 5^b is an enlarged perspective detail of the head, which supports the presser-feet. Fig. 5^c is a sectional detail of the end of the gage finger. Fig. 5^d is a perspective detail of the forward end of the feeder, enlarged; Fig. 6, a view similar to Fig. 5, taken 35 40 on the line x' , Fig. 2, Figs. 5 and 6 being taken in the same vertical section plane. Fig. 7 is a top view of the machine shown in the preceding figures, viewed from the left of Fig. 1, and partly broken off at the rear or feed end. 45 Fig. 7^a is a vertical section of the head and bed plate taken on the line x^3-x^3 , Fig. 7, viewed from the right-hand end of said Fig. 7, the cushion device being omitted. Fig. 7^b is a vertical section of the head taken on the 50 line x^4-x^4 , Fig. 7. Fig. 7^c is a vertical section, taken on the line x^5-x^5 , Fig. 7, of the tank and paste pan, to show the supporting webs and flanges, other parts being omitted for the sake of clearness. Fig. 7^d is an enlarged detail perspective view of the gage-carrier and its co-operating parts, said gage-carrier being turned into upright position to 55 show its construction. Fig. 8 is a horizontal sectional view taken on the line x^2 , Fig. 4, the 60 paste pan being omitted for sake of clearness. Fig. 8^a is a plan view of the brake mechanism and co-operating parts, the other details of the apparatus being omitted for clearness. Fig. 8^b is a detail of the brake mechanism to be described. Figs. 9 and 10 are detached detail 65 views in plan and end elevation respectively,

on a larger scale, of the lip or corner turners, shown in Fig. 9 as extended, and as folded in Fig. 10. Fig. 9^a is an under side view, on an enlarged scale, of the lip or corner turners, 70 showing the manner in which their supporting brackets are attached to the outer faces of the side wiper plates. Figs. 11 and 12 are views in plan and side elevation of a portion of the feeding mechanism. Fig. 12^a is a plan 75 view of the reciprocating feeder frame detached. Fig. 13 is an enlarged detail, partly in section, of one of the end pressure plates. Fig. 14 is a sectional view thereof, taken on the line $y-y$, Fig. 13. Fig. 15 is an enlarged 80 detail view in end elevation, partly broken away, of the wetting and pasting devices to be described, the tank being shown in section. Fig. 15^a is a sectional detail of the pasting devices, to be described. Fig. 16 is a detached 85 view of one of the two cams B which actuate rack bars to be described. Figs. 17 to 20 are detached views of other actuating cams, to be described, said cams being shown in their relative positions on the cam shaft when 90 viewed from the right-hand side of the machine as shown in Figs. 1 and 2, the cams C, E, and F facing the right-hand side of the machine, while the cam D faces to the left. Fig. 21 is a sectional view, and Fig. 22 a plan 95 view, of details of a modified form of cushion for the follower, to be described. Fig. 23 is an upper side view of the follower. Fig. 24 is a section thereof on the line $y-y$, with the plunger in position. Fig. 25 shows end and 100 side views of the locking devices on the plunger, to be described. Fig. 26 is a top view of a completed box, the shape of the blank being shown in dotted lines. Fig. 27 is a plan view of the bed of the apparatus below the 105 head, with the side and filling plates in position; and Fig. 27^a is a detail in perspective, to be described.

The side frames A, of suitable shape to support the operating parts of the apparatus, are 110 rigidly secured to or form part of a base A^x, and are connected and support at their tops a bed-plate A', of suitable shape to sustain the feeding and positioning devices to be described.

The side frames and base are provided with suitable pedestals supporting bearings A², A³, for a cam shaft A⁴, see Figs. 2, 4, 6 and 8, having thereon a series of cams B, C, D, E, and F, shown separately in Figs. 16 to 20, inclusive, the cams B at the outer ends of the shaft being similar, and oppositely faced.

As best shown in Figs. 3 to 6 inclusive, an arm E' preferably formed as a truss, is pivoted at E² to the base of the machine, and a 125 link E³, pivotally connected thereto at E⁴ is shaped to form a guide slot at its free end, as at E⁵, see Fig. 6, and shown in dotted lines Fig. 4, to embrace the cam shaft A⁴, the said link having thereon a suitable roller or other 130 stud E⁶, see dotted lines Figs. 2, 4 and 6, to enter and be actuated by the cam surface E^x.

of the cam E, the guide slot E⁵ acting to steady the link in its movements, as it is actuated by the cam to oscillate the arm E'.

The arm E' is herein shown as a truss, combining strength and rigidity thereby with lightness of construction, although it is obvious that any other suitable or desirable construction may be used.

The bed plate A' is rearwardly extended, as shown, at the feed end of the machine, see Figs. 11 and 12, and undercut plates a are secured thereto to form longitudinal guides or ways for the frame G, see Figs. 5 and 11, and shown separately in Fig. 12^a, to which is adjustably secured the feeder G', by suitable bolts g, the said frame G being connected to the upper end of the arm E' by a short link g', shown in section in Fig. 5 and in dotted lines in Figs. 3, 11 and 12, and thereby reciprocated horizontally back and forth in the guide ways a'.

The frame G is best shown in Fig. 12^a as skeleton in form to reduce its weight, and has longitudinal guide flanges G²⁰ upon its upper side.

The adjusting bolts g are extended through longitudinal slots g² of the feeder, whereby the position of the forward end of the feeder is adjusted to the width of the blank M, see Fig. 26, to be acted upon, such adjustment being necessary to adapt the machine to various widths of blanks, inasmuch as the throw of the frame G is constant.

The feeder is slotted centrally at G², see Figs. 7 and 11, to enable it to pass the central track b, to be described, extending to within a short distance of the former, as best shown in section, Fig. 5.

The forward end of the feeder G' is beveled as at 2, Figs. 5^d and 7, to readily pass under the blank, the said feeder, immediately back of its beveled front end 2, having attached to it plates g³, most clearly shown in Fig. 5^d, the front edges of the said plates meeting one of the long sides of the blank, it being supposed that the feeder and blank, not shown, are moving in the direction of the arrow 200, Fig. 7, the contacting edges of the said plates preventing the blank from slipping on the feeder while being fed. The plates g³ are attached to the feeder by suitable screws 3, whereby they may be readily replaced when worn.

Side tracks b' are secured to the upper portion of each paste pan H, parallel to the central track b, said tracks serving to support the blank, to be fed forward by the feeder, between the points where the said blank is wet and where it is pasted, or just outside the line on which the blank will be folded to constitute the ends of the box or cover.

The blanks M of paper-board, all properly notched, as in dotted lines Fig. 26, to form end and corner flaps and side flanges, are placed in a pile between suitable guides K,—herein shown as plates,—having at their op-

posite ends internally threaded bearings k, k', respectively, to receive therein the right- and - left - hand screw - threaded adjusting guide-rods K', K², the said guide rods being supported respectively in suitable stands k² erected upon the bed plate A', and in brackets k³ secured to the head of the machine. Like bevel gears k^x are secured to the rods K', K², best shown in Fig. 7, to engage gears k⁴ and k⁵ on a connecting shaft k⁶, suitably supported in bearings on the bed plate A', and as herein shown one end of the rod K² is shaped to receive a crank arm k⁷, see Fig. 1, whereby it may be rotated, such rotation, by means of the described bevel gears and connecting shaft k⁶, also rotating the rod K' to simultaneously move the guides K toward or from each other in parallelism, to rapidly and accurately adjust them to the length of the blank.

The guides are horizontally slotted, as at k⁸, see Figs. 3 and 5, to receive therethrough the shank of an adjusting screw k⁹, secured to a block k¹⁰ provided with a fin k²⁰, shown only in Fig. 7^d, to enter and be guided by the recess k¹² at the inner side of the guide K, see Fig. 5, the said block having pivoted thereto a gage carrier k¹³, extended laterally from the inner side of the guide, as best shown in Figs. 7 and 7^d, and to which carrier is rigidly secured a slotted finger k¹⁴ surrounding a threaded post k¹⁵. A spring s surrounds the said post between its head and the finger k¹⁴, as clearly shown in Fig. 7^d, and an internally threaded collar or nut k¹⁶ engages the threaded portion of the post between the block k¹⁰ and the finger k¹⁴.

The gage carrier k¹³ is slotted longitudinally to receive the shank of a set screw 5 attached to the vertical gage k¹⁷, see Figs. 1 and 7^d, the said gages k¹⁷ determining the position to be occupied by the rearmost side of the blank or pile of blanks nearest the feeding end of the machine.

The main adjustment is made by means of the set screws k⁹, by which the blocks k¹⁰ may be moved bodily along the guides K and secured in place, and the vertical gages k¹⁷ may be adjusted toward or from the center of the machine on the carriers k¹³ by the set screws 5, according to the length of the blanks. After the blocks have been adjusted to their approximate position, a finer adjustment may be given to the carriers by turning the nut or collar k¹⁶ on the threaded post k¹⁵, such movement turning the gage carrier k¹³ on its pivot and enabling a very fine adjustment of the vertical gages to be made.

It sometimes happens, when the blanks are cut from thin or light stock, that the ends thereof beyond the wetted portions, after receiving the paste, will bend or fall below the level of the tracks b, b', or out of a horizontal plane, resulting in an improper presentation of the blank to the former, and to obviate this bending and always present the blank in a

horizontal plane, I have provided adjustable auxiliary tracks b^2 beyond the said tracks b' , as best shown in Fig. 7.

The base of each guide K is slotted, as at 5 b^x , shown in dotted lines, Fig. 3, and in full lines at one side of Fig. 7, one of the guides K therein being shown as broken away, to receive therein an upturned threaded shank of a clamp block b^3 , see Fig. 3, and between the 10 top of the clamp and the bottom of the guide a slotted lateral extension b^4 secured to the auxiliary track b^2 is extended, the threaded shank of the clamp block extending through the slot in said extension and having at its 15 upper end a suitable clamping nut b^5 . By loosening the latter the pressure exerted by the clamp block upon the lateral extension b^4 is relieved, and the auxiliary tracks b^2 may be moved toward or from the guides K, and 20 also longitudinally along said guides by means of the slots b^x to adapt them to blanks of various sizes.

The side tracks b' are secured rigidly to and laterally adjusted with the paste pans H, lateral 25 adjustment of the said pans being accomplished by the slotted horizontal flanges h , see Figs. 5, 7, 7^a and 15, secured to the ends of the pans and resting on suitable supports, to be hereinafter described, and adjusting 30 screws 6 are extended through the slots of the flanges and into the supports.

An end gage or finger c is vertically movable in a suitable grooved head c' see Figs. 5 and 5^b having laterally extended ears or 35 flanges c², see dotted lines Fig. 7, and full lines Fig. 5^b, at its upper end to enter guide-ways c³ in a bracket c⁵, see Figs. 5 and 7 secured to or forming a part of the head of the machine, to be described, clamping plates c⁶, see Fig. 5, 40 secured to the under side of the bracket by adjusting bolts c⁶⁰ and forming the bottoms of said guide-ways maintaining the head c' in horizontally adjusted position, according to the width of the blank tightening or loosening the said bolts c⁶⁰ drawing the plates toward or removing them from the under sides 45 of the flanges c² of the head c'.

The end gage or finger c is engaged by the flanged base of an adjusting screw c⁷ having 50 its bearing in the head c', rotation of the set screw in one or the other direction raising or lowering the gage or finger to accommodate blanks of different thicknesses, as in United States Patent No. 498,976, dated June 6, 1893, 55 so that but one blank can be moved forward under it at the same time, and, inasmuch as different blanks in the pile of blanks will vary somewhat in thickness, the gage or finger is vertically adjusted to permit the passage 60 thereunder of the thickest blank that may be in the pile, and a yielding gage plate c^x is secured to the beveled lower end of the finger or end gage c, see Fig. 5^a, the said gage plate normally leaving sufficient space for the passage 65 thereunder of a blank of average thickness.

Should a thicker blank than the average

be presented, its leading edge will engage the yielding gage plate c^x and will press the same upward along the beveled end of the gage or 70 finger c against the pressure of a spring c^x, shown only in Fig. 5^a, until it has been raised sufficiently to permit the passage thereunder of said blank, and after the latter has been carried forward and positioned by the feeder, 75 the yielding finger will move back into its normal position, preferably by a spring acting thereon, as in the patent referred to, but not herein shown.

It is important to maintain the blank perfectly flat after it has been fed forward beyond the end gage or finger c, and in order to accomplish this, I have secured to the front of the grooved head c' one part c⁸ of an adjustable presser foot, see Figs. 5, 5^a and 5^b, 80 shown as a longitudinally curved metallic plate, slotted at c⁹ at its end adjacent the head, see Fig. 5^a, to embrace the end gage or finger c and permit the movement of the yielding gage plate c^x, the curved plate being held in 85 position on the head c' by set screws 7 extended through slots in an ear or lug c¹⁰ of the said plate, whereby the latter may be slightly adjusted in a vertical direction according to the thickness of the blanks. The 90 other part of the presser-foot is also shown as a curved plate c¹², cut away or slotted at c¹³, and supported by an upturned arm c¹⁴ thereon, which is connected to a carrier c¹⁵, see Figs. 5 and 5^b, adapted to slide and be 95 maintained in adjusted position in a suitable clamp formed by two like depending ears c¹⁶. The inner side of one of said ears is shown in Fig. 5, the outer side of one of the ears being shown in Fig. 5^b, the grooved head c' and end 100 gage or finger c having an opening therein to receive the end of the carrier, as best shown in Fig. 5, the opening in the end gage being clearly shown in Fig. 5^b. Suitable bolts c⁵⁰ are passed through said ears, and the latter 105 are drawn together thereby when the carrier c¹⁵ is to be clamped. In the said Fig. 5, the two parts of the presser are shown as pushed in, one upon the other, while in Figs. 5^a and 5^b they are shown as drawn out or extended 110 in order to more clearly illustrate their construction and manner of adjustment.

The part c¹² of the presser is moved toward or from the former to be described according to the width of the blank to be fed, and it will 115 be seen from the foregoing description and an inspection of Figs. 1 and 5, that the longitudinal edges of the presser foot will bear upon the upper side of the blank on somewhat widely separated lines after it has been 120 fed forward beyond the end gage c, maintaining it perfectly flat as it is presented to the former and preventing buckling of the blank.

A spring stop c¹⁷ is secured to the under side of the plate c¹², and extended to the end thereof or nearest the former, the said stop rising to 130 permit the passage of the blank as it is fed forward, but dropping back into its normal position, shown in Fig. 5, behind the rear edge

of the blank as soon as it has been moved beyond the stop, to prevent any possibility of the blank sticking to and being moved with the feeder on its rearward movement, as such retrograde movement would obviate its proper presentation to the former.

The side tracks b' terminate a slight distance beyond the forward edge of the tank H' , see Figs. 3 and 7, which contains the wetting devices, and the paste boxes, to be described, continuations of said side tracks being shown at b'' , see also Figs. 7^a and 27, formed on the inner edges of the longitudinally corrugated side plates b^6 , adjustably secured to the bed plate A' , as will be described, adjacent to the path of the reciprocating former, the corrugations on said plates supporting the projecting ends of the blank when the latter is in position over the former, and also affording a clearance space for any dirt or scraps of material which may adhere to the under sides of the blanks.

The side plates b^6 are grooved at their under sides, as at b^7 , best shown in Figs. 1 and 7^a, to receive the flanged portions d of the front filling plates d' , shown in Figs. 1 and 27, and omitted for the sake of clearness in Fig. 7, and also to receive the flanges d^8 of the back filling plates d^7 , see Figs. 7^a, 27 and 27^a, made longitudinally adjustable with relation to the plates b^6 by set screws d^9 extended loosely through lateral slots d^4 , see dotted lines Fig. 27, in the bed plate, and into the corrugated plates b^6 as shown in Fig. 7^a by dotted lines.

When the set screws or bolts d^9 are loosened, the pressure exerted by the side plates upon the front and back filling plates is taken off, and said plates b^6 and d' and d^7 at each side of the former opening may be simultaneously adjusted laterally as one piece, upon or with relation to the bed-plate A' of the machine, to adapt the same for a longer or shorter former and blank, the filling plates being held to the side plates by the flange and groove connection, the adjustment of the filling plates d' and d^7 longitudinally with relation to the side plates b^6 being accomplished by sliding therein along the side plates and thereby providing for variations in the width of the box.

Tightening of the set screws d^9 draws the side plates toward the bed plates and thus clamps the side and filling plates securely in adjusted position. A filling plate is located at each end of each side plate b^6 , at the front and rear of the path of the reciprocating former, respectively, but in order to avoid carrying the central track b up to the former, to support the center of the blank at its under side, I have cut the said track off at some little distance therefrom, as shown best in Fig. 5, and I have pivoted to the inner longitudinal vertical face of each of the back filling plates d^7 , shown separately in Fig. 27^a, at the rear side of the former a yielding track-like support or finger d^9 , see Figs. 5, 27 and 27^a, the forward end of which extends nearly to the rear side of the reciprocating former, and is normally

held a little above the top thereof by a suitable spring s^9 , see Fig. 27^a, one end of which is made fast to the pivot d^9 of the finger, and the other end to the plate d^7 which is suitably recessed to receive the pivot and spring.

As the blank is fed forward and its leading edge passes from the end of the central track, it rests upon the tops of these yielding supports, and as the feeder G' completes its forward movement, they are depressed thereby momentarily, and the central portion of the under side of the blank rests upon and is supported by them after the retraction of the feeder.

By cutting away the central track as shown, and securing the yielding supports to the adjustable rear filling plates, I am enabled to obtain a much greater adjustment for the width of the box or cover to be made than would be otherwise possible. The front faces d^{10} of the back filling plates are raised to the height of the continuations b'' of the side plates b^6 .

Each guide K is grooved longitudinally at its front end, as at m , to receive in it a fin on the outer side of a slide m' , see Figs. 1 and 5, held in adjusted position in said groove by a screw m^2 extended through a slotted portion m^3 of the groove m in the guide K , each of the said slides having formed thereon an edge guide m^3 , extended vertically upward, as clearly shown in Figs. 1 and 5, the lower ends thereof resting upon upturned ledges m^4 secured to the under side of the guides K , the said edge guides acting as stops to position the blank when the latter is ready to be moved vertically by the former, to be described, and clamped between it and the follower, so that the blank will be raised in a truly horizontal position, and it will be noticed in Fig. 1 that the said stops extend slightly above the horizontal plane occupied by the bottom of the follower when in normal position.

The projecting ledge m^4 on the bottom of the guide forms a sort of track to keep the pasted portion of the blank from contact with the plate b^6 .

The bed plate A' is cut away at the point where the pile of blanks is supported, and has secured thereto a vat or pan H' , which contains the water to be used for wetting the blanks prior to feeding the same, the wetting being along the dotted and full lines x^{20} , shown in Fig. 26, and along the full lines showing the bent over sides of the box. This vat or pan H' contains wetting devices or wetters, herein shown, see Figs. 7 and 15, as a series of blocks e , grooved or recessed at their upper ends to receive sections of felt or other absorbent material e' , to constitute the acting surfaces of the wetters. These blocks are recessed at their under sides, see dotted lines Fig. 15, to receive loosely the preferably conical ends of bearings e^2 of skeleton holding frames e^3 , supported in longitudinally recessed or grooved supports e^3 , each secured to a block e^4 adapted to slide horizontally in

an undercut clamping groove e^5 , formed in the top of a standard e^6 secured to a yoke e^7 , shown only in Figs. 5 and 15, mounted upon or fixed to a spindle e^8 extended up through 5 a suitable stuffing box e^9 , see Fig. 4, attached to the bottom of the vat H' , the vertical movement of the said spindle by or through a short link e^{10} , connected to one arm e^{11} of a rock-shaft e^{12} , see Fig. 6, causing the wetters to be 10 raised and lowered in the vat.

The rock-shaft e^{12} , suitably supported in bearings on pedestals A^{3x} , has rigidly secured thereto an arm F' , to the outer end of which is secured a suitable roller or other 15 stud F^2 to enter and be actuated by the cam surface F^x of the cam F , the rotation of which by shaft A^4 causes the wetters to rise at the proper time and moisten the blank parallel to its front and rear edges along the 20 lines upon which it is to be bent. Wetting devices are also supported in grooved holding frames e^{13} , at right angles to the frames e^3 , supported upon uprights e^{14} suitably secured to slides f adapted to be longitudinally 25 moved on the yoke e^7 toward or from the center of the machine, the said slides forming the bases of spindles f' extended through suitable stuffing boxes f^2 in the bottom of the 30 paste pans H , to be described, lateral adjustment of said paste pans and their entering spindles also adjusting the longitudinal wetters, the slides f being held in adjusted position on the yoke e^7 by set screws 500. See Fig. 15.

Referring to Figs. 7 and 15, it will be seen that, inasmuch as the side tracks b' are rigidly secured to the paste pans, and the longitudinal or end wetters to the slides f , any lateral adjustment of said paste pans, and 40 necessarily of their spindles, will also and simultaneously adjust the side tracks b' and the end wetters, so that they will always be maintained parallel and the same distance apart, the one adjustment answering for both.

The inner sides of the end wetter holders e^{13} are slotted, as at e^{15} , see Fig. 5, and when a very long blank is used, the lateral wetting devices are extended, the outer end of the endmost holding frame e^x resting in the slot 50 e^{15} , while the inner end of the frame rests in and is maintained upright by the lateral support e^8 described. The slots e^{15} are of sufficient length to admit of considerable adjustment of the transverse wetters, the lateral 55 supports e^8 thereof being held in adjusted position by the clamp e^{16} forming one side of the undercut groove e^5 , as best shown in Fig. 15, formed in the top of the standard e^6 .

As best shown in Fig. 5 the transverse wetters are independently adjustable and have independent supports e^6 therefor, said supports being secured to the yoke e^7 at the front and rear of the spindle.

A suitable hand hole provided with a cover 60 20 is made in one wall of the tank or vat H' , whereby access to the lower part may be had when desired. A horizontal web or flange h^x

is formed in the upper part of each corner of the tank or vat H' , see Figs. 7 and 7^a and the horizontally extended slotted ears h of the 7 paste pans rest upon the said webs h^x to thereby sustain the paste pans in the vat, and held in adjusted position by the set screws 6 extended through the said ears and into the horizontal webs.

The pasting devices are shown in Figs. 7, 15 and 15^a, a portion of one of the paste pans H being broken away in Fig. 15 to better show the internal arrangement thereof, the pasters being shown as a series of blocks f^3 , grooved 80 at their upper edges, the said blocks being shown as slotted or forked to embrace and rest upon a flexible tubular bearing f'^x , preferably mounted upon the longitudinally grooved upper side of bars f^4 , notched as at f^5 , to keep 85 the blocks in position parallel each with the other and to prevent them from twisting upon the bars, said bars being held in place by projecting under cross bars f^9 .

In Fig. 7, I have shown the pasters as applied to all of the bars, and in practice, it will be noticed that the said bars may be more or less filled up with these pasters, according to the size and shape of the part of the blank to which it is desired to apply the paste.

As best shown in the detail Fig. 15^a, the bars f^4 are yieldingly supported by springs f^5 secured at their lower ends to the holder f^7 , suitably recessed to receive them, the bars f^4 being held from upward displacement by the 100 cross bars f^9 which are secured to the holder, and the holder in turn is provided at its under side with a hub or collar to receive the top of the spindle f' , to which it is clamped by a set screw f^8 , extended through the collar 10 to bear against the spindle. The entire pasting device may be removed bodily from the paste pan by loosening said set screw, and detaching the holder from the spindle.

Inasmuch as the pasters are independent, 110 they may be applied to the bars f^4 in such number and position as to accommodate a blank of any desired shape.

As has been stated, the spindles f' are secured to the slides f carried by the yokes e^7 , 115 so that the pasters rise and fall in unison therewith and with the wetting devices already described.

When the pasters rise with the wetters, they pass up through the paste in each paste 120 pan H , and lift portions of the paste up against the blank above it—that is, the blank at the bottom of the pile of blanks, applying paste to the blank as at 75, Fig. 26. The grooved tops of the blocks f^3 retain in them 125 more or less paste, depending upon the depth of the grooves. The wetters and the pasters thus operate on the blank to wet the same and paste it at the proper places, and thereafter the actuating mechanism of the feeder G' 130 moves it forward, as described, to engage the wet and pasted blank, and carry it forward along the tracks into position above the former.

It may be herein stated that standards H^2 are secured to the bottom of the tank H' to support guide-ways H^3 for the under side of the feeder in its reciprocations, the central track b also being supported by a cross frame 30 secured to the guide-ways H^3 said frame being shown in section Fig. 5. Other guide-ways H^4 and H^5 are provided at the rear and front of the tank H' , shown in dotted lines 10 Fig. 5 the guide ways H^5 being very clearly shown in Fig. 7.

The former over which the blank is bent to give shape to the box or cover to be made, is composed of a rectangular casting N , preferably of hardened steel, and of the exact size and shape of the interior of the box or cover. The said former is adapted to rise and fall through an opening in the bed plate A' of the machine, of sufficient size to accommodate the 20 largest former to be used, the effective opening for the passage of the former being adjusted and formed by the longitudinal side plates b^6 , and the filling plates d' , d^7 heretofore described, and clearly shown in Fig. 27 25 which are adjusted to the size of the former to be used.

Vertical guide-ways N' are secured to the base of the machine and to the bed plate A' , to which cover plates N'^x are attached, to receive and guide a reciprocating cross head T having rack bars T' secured to or forming a part of the vertical rear sides thereof, to be engaged by the toothed portion of like gears L secured to a short shaft L' , supported in suitable bearings L^x on the guide ways N' , as best shown in Figs. 6 and 8, a small pinion L^2 being also secured to the shaft L' and provided with teeth upon a portion of its periphery.

40 An arm L^3 , see Fig. 4, provided with rack teeth L^4 at its upper end and in engagement with the teeth on the pinion L^2 , is shaped at its lower end to form a slot L^5 , see dotted lines Fig. 4, embracing the cam shaft A^4 , and a 45 roller or other stud L^6 to be acted upon by the cam D , is secured to the arm L^3 , rotation of the said cam raising and lowering the bar L^3 , and, by means of the teeth L^4 , rotating the pinion L^2 and thereby the shaft L' , first in 50 one and then in the other direction.

As shown in the drawings, the bar L^3 is at its lowermost position, and at rest, and it will be seen that as the said bar rises, it will rotate the gears L on the shaft L' in the direction of the arrow 100 Figs. 4 and 6, the toothed portion of said gears at such time engaging the rack teeth T' of the cross-head, and raising it, the upper end of which is secured to the under side of the former N by a threaded bolt N^2 , extended through an opening in the horizontal face of the former, and secured by a set nut N^3 .

By the construction herein described the former and cross-head are reciprocated vertically, the cross-head in rigid guide-ways, so that no vibration thereof is possible, the rotary motion given to the shaft L' being trans-

formed into linear movement of the cross-head by means of the gears L and rack teeth T' , such mechanism insuring a positive, powerful and steady reciprocation of the former. 70

A guide roll L^5 , see Figs. 4, 6 and 8, is supported in bearings N^4 on the guide ways N' to bear on the upper smooth face of the bar L^3 , and thereby keep the teeth L^4 in engagement with the pinion L^2 . 75

The toothed portions of the gears L and the pinion L^2 are so arranged with relation to each other that the former N completes its movement in either direction simultaneously with 80 the throw of the bar L^3 .

The bed plate A' has secured thereto standards D^3 to support the transverse braces D^3 of the head D^4 , which sustains and guides the follower, to be described, and also the co-operating parts which act to turn the sides and ends of the blank over upon the former, and the devices to thereafter compress the same to form the box or cover. 85

Referring now to Figs. 1, 5, 7, 23 and 24, the follower D^5 is shown as detachably secured to the lower end of a slotted slide-rod D^6 extended through a sleeve D^7 forming a fixed part of the yoke-like portion of the head D^4 , and a cylinder D^8 is secured to the upper end 95 of the slide-rod D^6 , said cylinder having therein a piston D^9 , secured to a piston rod D^{10} , which is extended within and guided by the slotted slide rod D^6 , and the piston rod is held in its normal position, shown in Figs. 1 and 5, 100 by a suitable spring-latch l mounted upon the sleeve D^7 , the end of the latch extending into a recess 200 in the lower end of the piston rod. See Figs. 1, 5 and 7a.

A small vent or opening 60 is made in the 105 top of the cylinder D^8 , through which air enters into or is discharged from the cylinder above the piston.

When the follower is raised, as will be described, the air underneath the piston forms 110 a cushion, preventing sudden shocks, and the space above the piston is filled with air, so that when the follower descends the air will be slowly expelled through the vent 60 , and the descent of the follower will be cushioned 115 thereby.

In order that the air may pass from the under to the upper side of the piston D^9 I have provided the latter with a small passage 65. Shown in dotted lines Fig. 5. 120

The weight of the follower D^5 is increased, and its movements steadied, by attaching a heavy annular weight W to the cylinder D^8 .

The lower end of the slide rod D^6 is reduced, as at l' , Figs. 5, 24 and 25, and provided with 125 oppositely extended ears l^2 , while the follower has a hub D^{6x} formed upon its upper side, in the opening of which are two opposite inwardly projecting ledges l^3 , leaving the opening of the shape shown in Fig. 23, to receive 130 the end of the slide rod, which is inserted therein until the ears l^2 pass below the plane of the ledges l^3 , after which the follower is turned through an arc of ninety degrees thus

bringing the ears l^2 beneath the ledges l^3 , and supporting the follower thereby, the shoulder l^4 of the slide-rod D^6 preventing the follower from being displaced.

5 The follower is normally held from any rotation upon the slide-rod by the side wiper plates i and end pressure plates s^{10} , to be described as shown best in Fig. 5. With the parts in the position shown in said figure the follower could not be removed from the slide-rod, as it could not be rotated thereon, so when it becomes necessary to remove or replace a follower, the latch l is withdrawn from engagement with the recess 200 of the piston-rod, permitting it to drop, and consequently allowing the slide rod to fall through the sleeve D^7 until the bottom of the cylinder D^8 rests upon the top of the sleeve. The follower is thus brought below the lower edges of the side wiper and end pressure plates, and it can be rotated sufficiently upon the slide-rod to enable it to be removed therefrom. In practice, the area of the follower will be slightly larger than the area of the former, the difference being usually about one thirty-second of an inch.

Side wiper plates i which carry the lip turners to be described, are supported in an adjustable manner in the cross-braces D^3 , at the front and rear of the follower, and are provided with extensions i' rectangular in cross section and fitting in guide-ways in the cross-braces D^8 . See Figs. 1 and 5. Each shank i' in practice is provided with a threaded hole 35 in its outer end to receive the threaded portions of adjusting rods i^2 , extended through suitable bearings in the head in which they may be rotated by suitable hand wheels 52, but restrained from longitudinal movement by 40 slotted plates 50 embracing annular grooves 51 in the shanks of said rods. The extensions i' of the side wiper plates are of sufficient width, see dotted and full lines Fig. 7, to afford a firm support for the said plates, to maintain their inner acting faces in truly vertical position, and by means of the adjusting rods 45 i^2 the said plates are adjusted toward or from the path of the follower and former according to the thickness of the blank to be acted upon, or the size of the former to be used.

Suitable brackets n , n' , see Figs. 1, 9, and 9^a are secured to the outer faces of the side wiper plates i , see Figs. 1, 9 and 9^a by bolts n^{20} , to form bearings n^x , n'^x , for like rock shafts 55 n^2 , having a longitudinal groove n^3 therein, see Fig. 9 the said bearings being located at the lower edges of the wiper plates, as shown in Fig. 7^a, and at the extremities of the rock-shafts, and such a distance apart that the lip 60 turners now to be described, may be adjusted outwardly for the largest sized box or cover to be made on the machine, the said shafts n^2 being provided at one end with bevel gears n^4 , as clearly shown in Figs. 9 and 10, to be 65 engaged by like gears n^5 , splined to and rotatable with an actuating shaft n^6 supported in bearings n^7 in the brackets n' , and in a

bracket n^{15} , see Figs. 7^a, 9, 9^a and 10, secured to the side of the head the bevel gears n^5 being longitudinally movable on the actuating shaft n^6 , when the side wiper plates, to which the brackets are attached, are adjusted. The gears n^5 are normally held from longitudinal movement by the bearings n^7 and the bevel gears n^4 .

75 A pinion n^8 is rigidly secured to the actuating shaft n^6 and in engagement with a rack bar n^9 , see Figs. 1, 9 and 10, upon the upper end of a link n^{10} , jointed at its lower end to a rocker arm n^{12} which is pivotally connected 80 to the side frame n^{13} and having thereon a roller or other stud n^{14} , Figs. 2, 4 and 8, adapted to enter and be actuated by the cam groove C^x on the gear C , the groove being omitted from Fig. 4 for the sake of clearness, but 85 shown in full lines Fig. 17, rotation of the said gear C at the proper time reciprocating the link n^{10} and causing a rotation of the actuating shaft n^6 in one and then in the other direction, and through the bevel gears n^5 , n^4 , 90 causing rotation of the grooved shafts n^2 in opposite directions.

I have herein shown the lip turners as adapted to act upon the blank to first turn the side flanges 90 thereof, see Fig. 26, down 95 bodily upon the vertical faces of the former, and to thereafter bend the ends of the said sides or the corner flaps 95 about the corners of the former and over upon the end faces thereof, and to hold the portions so bent in 100 such position until the former in its continued vertical movement has carried the bent blank, grasped between the former and follower, above and beyond the lip or corner turners, and against the inner faces of the side wiper 105 plates i , hereinbefore described, which maintain the sides of the box or cover against the former while the end pressure plates, to be described, are moved forward to compress the pasted ends 77 of the blank upon the corner 110 flaps, as will be described, the ends 77 having been previously bent down as hereinafter described.

The lip or corner turners are herein shown as compound and composed of folding plates 115 or wings o and o' , the former provided with hubs o^x loose on the shafts n^2 , hubs o'^x being splined by keys 300 to the shafts n^2 to rotate therewith, each of said hubs o'^x having thereon a segment bevel gear o^2 to engage a 120 similar gear o^3 on the end of a pintle o^4 , extended through suitable like ears o^5 on and pivotally connecting the plates o and o' , a set screw 12 extended through one of the ears o^5 of each wing o' bearing against the pintle 125 o^4 and thereby causing the said wings to move with the pintle when it is rotated on its own axis, a spring s' being secured at one end to the plate o' and at its other end to the pintle o^4 , the action of the spring normally unfolding the plate o' , as shown in Figs. 1, 5, 9 and 9^a, and maintaining it in the same plane with the plate o .

130 The folding plates forming the lip or cor-

ner turners are held in unfolded or extended position, as shown in Figs. 1, 5, 9 and 9^a, until the former has raised the blank against the follower.

- 5 When the blank has been firmly clamped between the former and follower and before it is carried upward between the side and end plates, the shafts n^2 are rotated in the direction of the arrows Fig. 9, and the toothed 10 hubs o'^x are turned therewith to positively swing the plates o and o' , still extended or unfolded, down from the position shown in Figs. 1 and 5, into vertical planes parallel to the front and rear faces of the former, thereby bending the projecting side flanges 90 of the blank over against the vertical sides of the former, the spring s' being of sufficient strength to maintain unfolded and move the two plates of each lip turner as one, in over 15 coming the resistance offered by the blank to bending, but as soon, however, as the sides of the blank are brought against the vertical faces of the former, further movement of the plates o is prevented thereby, and as the 20 shafts n^2 continue to rotate, the geared hubs o'^x moving therewith and engaging the segment gears o^3 on the pintles o^4 , will rotate the same in the ears o^5 of the wings o , thereby turning the plates o' , fixed to the pintles by 25 the screws 12, into the position shown in Fig. 10, at right angles to the plates o , such movement bending the ends 95 of the side flanges of the blank sharply around the vertical corners of the former and pressing such bent 30 portions or corner flaps against the ends of 35 the former.

The corner turners are held in adjusted position upon the shafts n^2 and restrained from longitudinal movement by clamp collars o^6 , which can be rigidly clamped upon the shafts at the desired points, and as they are shown between the hubs o^x of the plates o , in Figs. 9 and 9^a they prevent longitudinal movement of the lip or corner turners as a 40 whole.

The cam groove C^x by which the reciprocations of the rack bar n^9 is controlled is of such shape that the corner turners are maintained folded and closed upon the corners of 45 the blank until the former has moved upward sufficiently to carry the blank above them and into position to be held by the side and end plates.

By the hereinbefore described construction 50 of the corner turners, the corners of the box or cover are sharply defined and positively made, and with much greater accuracy than would be otherwise possible, while rapid and extended adjustment for different sizes is 55 readily secured.

The supports D^2 have suitable bearings formed therein to receive and properly hold four pressure screw shafts R , R' , R^2 and R^3 , the said shafts extending across the head and 60 having secured thereto at their opposite ends like gears r , all of which are engaged and partially rotated by reciprocating racks R^4 ,

one at each side of the machine, each rack having a slot as r' to receive a guiding stud screw r^2 , substantially as shown in United States Patent No. 418,690, referred to.

Each rack bar is provided with an extension cut away as at R^5 to embrace the cam shaft A^4 , and is provided with a roller or other stud R^6 to enter a groove B^x in the cam B , 75 there being two such cams, one at each end of the shaft A^4 , the extensions being additionally guided by grooved bearing rolls r^3 , suitably secured to the side frames.

The shafts R and R' at the left side of the 80 machine, viewing Fig. 1, are provided with right hand threads while at the right side of the machine said shafts are provided with left hand screw threads, and the shafts R^2 , R^3 , at the left side of the machine are provided with left-hand screw threads, the same shafts at the right side of the machine being provided with right hand screw threads.

A pressure head S is supported upon the threaded portions of the shafts at the left side 90 of the machine, and a like pressure head S' is supported at the right side of the machine by the threaded portions of the said shafts at that end thereof, each of said pressure heads having at each of its ends two like internally 95 threaded sleeves S^x , see Figs. 1 and 7 each sleeve fitting the threads on the pressure shaft, for moving the pressure heads S and S' , positively, moving them backward and forward, with their attached parts, to be described, the said pressure heads being moved up against the partially made box held between them upon the former, to compress the pasted ends of the box upon the corner flaps, previously turned over as described.

Each sleeve is mounted loosely in the pressure head so as to rotate therein, and has attached to it a pinion or gear S^2 , and each pair of pinions or gears S^2 is engaged and rotated by one intermediate gear S^3 , adapted to rotate on a stud S^4 , see full and dotted lines Fig. 7, and in full lines Fig. 7^b carried by the pressure head. There are two intermediate gears S^3 for each pressure head, and they mesh together, one intermediate gear of each pair 110 having attached thereto or to rotate therewith a worm gear S^5 clearly shown in Fig. 7^b, which is engaged and adapted to be rotated by a worm on a vertical shaft S^6 , having its bearings S^{50} secured to or forming a part of the 115 pressure head, said shaft S^6 being provided at its upper end with a suitable handle S^7 , by which it may be turned by hand, when it is desired to adjust the pressure heads toward or from each other, to adapt the end wipers 120 or plates carried by them, to the thickness of the blank, and also to the size of the particular former to be used.

With the pressure heads S , S' properly adjusted to the size of the blank, they are reciprocated toward and from each other during the completion of each box or cover, and toward and from the former N by the reciprocation of the racks R^4 , as described, and

- similarly to the operation in Patent No. 418,690 referred to. In said patent, however, the end wiper plates were rigidly held on the pressure heads, and in case of any irregularity in thickness of the blank on the former the thinner portion of the blank was not subjected to sufficient pressure, and frequently the corner where the stock was thinnest would not be properly pressed smooth or united.
- 5 To obviate this trouble I have attached each end wiper plate s^{10} to a bearing block s^{11} , see Figs. 7, 7^a, 13 and 14, having preferably a convexed back s^{12} , to rest in a suitable concavity in the pressure head as a seat, said blocks being adapted to rock on or about vertical pivots s^{13} , which enter and take bearings in lugs s^{14} and s^{15} , attached to the top and bottom respectively of the pressure head by suitable screws.
- 15 2c The upper lug s^{14} is pivoted at s^{16} to the pressure head and notched, as at s^{17} , to embrace the pivot s^{13} , the other end of the lug having a spring catch s^{18} see also Fig. 7^a adapted to enter a recess in the pressure head 25 and hold the lug in the position shown in Figs. 7, 7^a and 13.
- Should it be necessary for any reason to remove an end wiper plate s^{10} , the spring catch s^{18} is withdrawn and the lug s^{14} swung to one side to disengage the pivot s^{13} from the notch s^{17} , after which the wiper plate may be readily lifted out from its seat.
- 30 The pressure head has, as best shown in Fig. 14, recesses s^{19} formed therein on opposite sides of the vertical concavity in its face, said recesses being threaded to receive the threaded sleeves s^{20} , provided at their outer ends with polygonal heads s^{21} , by which they may be rotated and adjusted in or out of the 35 recesses. Headed shanks s^{22} are extended through the sleeves, and nuts s^{23} are secured upon their projecting inner ends, to prevent them from being forced outwardly by the pressure of a coiled spring s^{24} , surrounding 40 said shank within the sleeve, the spring bearing upon the head of the shank and the inner end of the sleeve.
- 45 The heads of the said shanks are preferably rounded, as at s^{25} , and are projected beyond the heads s^{21} of the sleeves by the force of the 50 springs to bear against the backs of the bearing blocks s^{11} at each side of the convex portion, so that the end wiper plates s^{10} and attached blocks are free to rock slightly in the 55 pressure heads to adapt themselves to any variations in the thickness of the ends of the blank, longitudinal adjustment of the shanks being made by moving the threaded sleeves in or out of the recesses, as may be necessary.
- 60 6o Inasmuch as the headed shanks are held in the pressure blocks by the threaded sleeves, it will be evident that the end pressure plates may be removed and replaced without interfering at all therewith.
- 65 65 After the sides and corner flaps of the blank have been bent over about the former N, as described, the former is raised, and the ends

77 of the blank come in contact and are bent down by the bottoms of the end wiper plates s^{10} .

70

The toothed gear C on the shaft A⁴ engages a pinion C', see Figs. 4 and 8 fast on a shaft C² supported in suitable bearings, said shaft having thereon a large gear C³ which in turn engages a pinion C⁴ on the main or driving 75 shaft C⁵, said shaft having loose thereon a belt pulley C⁶ forming one part of a friction clutch C⁷, see Figs. 4 and 6, of any usual or well known construction, rotatable with the shaft, C⁵, and operated by the usual cone C⁸ 80 actuated by a yoke C⁹, on a rock shaft C¹⁰, operated by the lever C¹¹.

It is most desirable to be able to stop the machine very quickly at times, and in order to do so I have secured to the driving shaft 85 C⁵ a brake wheel B', see Figs. 4, 6, 8 and 8^a, adapted to be engaged by a friction shoe B², secured to a carrier B³ pivoted at 80 to the base of the machine, see Fig. 6 said carrier having pivotally secured thereto at its outer 90 side an internally threaded collar B⁴ engaged by the threaded end of a rod B⁵, the other end of said rod, also threaded, but in the opposite direction entering a similar threaded sleeve B⁶ pivoted to a suitable stand B⁷, said rod 95 having formed thereon or secured to it between its ends a toothed gear B⁸, in engagement with the teeth of a rack bar B⁹, slotted to embrace the said gear, see Fig. 8^b, and connected by a rod B¹⁰ to an arm B¹¹ of the rock 100 shaft C¹⁰.

When the lever C¹¹ is moved to the right, viewing Fig. 2, the clutch will be moved into engagement with the belt pulley C⁶ to rotate the same, the movement of the rock-shaft C¹⁰, 105 also moving the rod B¹⁰ to the right, Fig. 2, and in the direction of the arrow Fig. 8^a the rack bar B⁹ at such time rotating the threaded rod B⁵ in its sleeve-like bearings B⁴ and B⁶, the opposite threads causing them to move 110 toward each other to thereby draw the shoe B² and its carrier B³ toward the sleeve B⁶, and consequently away from the brake wheel B'.

When the machine is running and it is desired to stop it, the handle C¹¹ is moved to the 115 left, Fig. 2, thereby throwing the clutch out of engagement, and at the same time rotating the threaded rod B⁵ in the proper direction to partially unscrew from and separate the bearings B⁴ and B⁶, and thereby force the carrier B³ and its shoe B² firmly against the brake wheel, in a most powerful and efficient manner, the power applied to the shoe being great enough to deflect the main shaft C⁵, were it not for the guard shoe B¹² pivotally supported 120 at the opposite side of the brake wheel, as clearly shown in Figs. 4, 6, 8 and 8^a.

The application of the brake is simultaneous with the releasing or disengagement of the clutch, and is so effective and rapid in 125 operation that the machine may be stopped, when running at full speed, in less than half a revolution of the main shaft.

Referring now to Figs. 11 and 12, I have

shown a piston G^3 secured to the feeder frame G , adapted to enter an open-ended cylinder G^4 when the feeding frame is retracted preparatory to engaging a blank to feed the same, 5 the piston G^3 compressing the air in the cylinder G^4 to thereby form a cushion for the feeder and its frame, to obviate a shock at the end of its rearward throw due to the momentum of the moving parts. The cylinder 10 G^4 is suitably secured to the extended portion of the bed plate A' , as herein shown, by bolt 40, and the piston G^3 may have any suitable packing applied thereto to make it tight in the cylinder, while a suitable opening or openings 15 will be made in the end of the cylinder to permit the compressed air to pass slowly therethrough.

I have shown a modified form of supporting and cushioning mechanism for the following in Figs. 20 and 21, wherein the sleeve D^{7x} in the head D^4 is somewhat lengthened, and heads t, t' , are secured to the top and bottom thereof, having openings therethrough to admit a slide rod t^3 , to the lower end of 25 which the follower D^5 is secured, and a piston t^3 is secured to said rod within the cylindrical sleeve D^{7x} , the slide rod extending above the bearing and through its head t' , to receive thereon a stop collar t^4 , to limit the 30 extreme downward movement or drop of the follower, said collar normally resting on the top of a locking device, shown as a hub-like block t^5 pivoted to the head t' and normally held in the position shown by the spring t^6 . 35 See Fig. 21. By moving the locking block to one side, away from the path of the collar t^4 , the latter will descend until it rests upon the head t' of the sleeve D^{7x} , thereby lowering the follower sufficiently to permit it to be readily 40 removed from the lower end of the slide rod t^3 . To cushion the follower on its upstroke, I have shown a spiral spring t^7 , loosely encircling the rod t^3 and supported by the piston t^8 , the said spring being compressed between 45 the piston and head t' when the follower is raised. In the modification just described, the piston t^8 may be made tight enough to compress the air between it and the heads t, t' , if desired, and serve as an additional 50 cushion.

In operation a series of blanks, notched at their ends, substantially as in Fig. 26, are placed between the guides K with their front and rear edges against the gage or finger c , 55 and the gages K^{17} respectively the lowermost blank of the pile of blanks resting upon the tracks b, b' , and upon a portion of the auxiliary tracks b^2 , the tracks being so arranged as to permit the wefters to pass up between 60 them.

In practice the pasters are arranged according to the shape and size of the blank, and so as not to interfere with the auxiliary tracks b^2 , and in Fig. 7 some of the pasters have been 65 removed from beneath the said tracks so that when the pasters rise to apply paste to the under side of the blank there will be a vacant

space on the paster supports underneath the tracks, and there will be no interference therewith.

The drawings show the machine with the feeder as having passed over a sufficient portion of its forward stroke to move the undermost blank of the pile forward underneath the presser feet c^8, c^{12} , prior to completing the forward stroke to position the blank upon the former and underneath the follower; but prior to the forward movement of the feeder the wetting devices will have been raised to wet the under side of the blank in the dotted lines x^{20} shown in Fig. 26, and along the lines where the side flanges 90 are shown as bent up, thus slightly moistening the stock to prevent the same from cracking when bent or folded. The pasters, as has been described, 85 will also be lifted to apply paste to the end flap of the box or cover, as shown at 75, in Fig. 26. The blank, having been wet and pasted, is moved forward by the feeder under the gage or finger c , and the presser feet c^8, c^{12} , the space below the finger being sufficient to permit one blank to be so fed forward at a time, as has been described, the feeder carrying the blank forward until its leading edge meets the vertical gages m^3 before referred to, which act as stops for and to correctly position the blank. The said gages m^3 are herein shown as properly positioned to stop a blank in which the ends of the leading corner flaps 95 are cut along the dotted lines 95 95^x , Fig. 26, so that the edge engaged thereby would be the front edges of the end flaps 77. If the front edge of the leading side flange 90 were to be engaged by the gages m^3 the latter would be moved toward the front of the 105 machine from the position shown in Fig. 5. When the blank is thus positioned over the former N , the latter is raised by the mechanism hereinbefore described, the said former carrying with it the wetted and pasted blank 110 to meet the under side of the follower B^5 , the gage m^3 during such time acting against the end of the blank to keep the same in position during its vertical movement, so that the blank is in the proper position with relation 115 to the former to be bent or folded in the desired lines. As soon as the blank is brought up against the under side of the follower the latter begins to rise, owing to the continued movement of the former, the blank being 120 firmly grasped or clamped between them. While the blank is thus clamped between the follower and former the upward movement ceases, and the lip or corner turners, which then stand at the level of the top of the former, 125 are positively actuated, as described, to bend the side flanges of the blank over the front and rear vertical faces of the former, after which the plates o' of the corner turners bend the corner flaps or ends of the side 130 flanges around the former and against its ends. Immediately thereafter, and while the corner turners are held in the last named folded position, the upward movement of the

former is resumed, thereby carrying the bent blank upward into position between the side wiper plates i , and the end wiper plates s^{10} , the latter bending down the end flaps 77 upon 5 the corner flaps 95, and when the blank is in proper position between the end and side wiper plates the racks R^4 actuate the shafts R , R' , R^2 , R^3 , as described, to move the pressure heads S and S' toward each other and 10 the former, to press, as described, the end wiper plates s^{10} against the ends of the blank, forcing them tightly and smoothly against the corner flaps, to thereby set and hold the paste previously applied to the end flaps, thus completing 15 the box while the former remains stationary. The box or cover having been completed, by such compression, the former descends, the racks R^4 having been lowered to rotate the shafts R , R' , &c., in the opposite 20 direction, to withdraw the end wiper plates s^{10} away from the end flaps of the box, so that the latter is free to descend with the former, the follower following it in contact with the box until the stop latch l in the depression 25 200 in the piston-rod D^{10} prevents its downward movement, and consequently limits that of the follower, unclamping the box, which moves down with the former until the down-turned edges of the sides and ends of the 30 box come against the tops of the plates b^6 and d' , which then act as clearers, stopping the descent of and stripping the box or cover from the former, which continues to descend until it is in its normal position ready to receive 35 the next blank to be fed. The box or cover thus stripped from the former is left standing upon the said plates, and is now discharged from the machine, which is accomplished by an ejector w , shown in Figs. 1, 5 and 7, striking 40 the box and throwing it out at the delivery end of the machine, this being done at the same time that the feeder is acting to carry forward a wetted and pasted blank.

The ejector w is shown as a curved rod, carried 45 by a vertical rock-shaft w' held in suitable bearings in the side of the machine, and having at its lower end suitable roller or other studs w^2 , w^3 , in the path of movement of and to be acted upon in turn by a cam lug w^4 , secured 50 to the side of the cam F , see Figs. 2 and 8, said cam lug acting to turn the rock-shaft quickly in its bearings and thereby throw the ejector inward to strike the box or cover a smart blow and throw it from the machine, the return of the ejector into its normal inoperative 55 position being aided and quickened by a strong spring w^5 coiled around the rock-shaft and secured at one end thereto, the other end of the spring bearing against some fixed 60 part of the machine.

This invention is not restricted to the exact construction and arrangement of parts as herein shown and described, as the same may be altered or modified without departing from 65 the spirit of my invention.

In the claims the term "box" is also intended to include a cover, inasmuch as a cover

is nothing more than a box with low sides and ends, and as will be evident, my herein described apparatus is equally applicable to the manufacture of either.

I claim—

1. A former upon which a blank is supported to be shaped, and compound lip turners located adjacent the corners thereof, combined with actuating mechanism to automatically move the lip turners bodily toward the former and thereby turn projecting portions of a blank against some of the walls thereof, continued operation of said mechanism turning a portion of each lip turner about the corners of said former while the other portions remain at rest, to bend the corner flaps of the blanks inwardly toward the ends of the former, substantially as described. 85

2. A former upon which a blank is supported to be shaped, compound lip turners located adjacent the corners thereof, and adjusting devices for and to regulate the distance between said lip turners, whereby they 90 may be made to co-operate with formers of different sizes, combined with actuating mechanism to automatically move the lip turners bodily toward the former and thereby turn projecting portions of a blank against some 95 of the walls thereof, continued operation of said mechanism turning a portion of each lip turner about the corners of said former while the other portions remain at rest, to bend the corner flaps of the blanks inwardly toward 100 the ends of the former, substantially as described.

3. A former upon which a blank is supported to be shaped, compound lip turners located adjacent the corners thereof, and actuating mechanism to automatically move the lip turners bodily toward the former and thereby turn projecting portions of a blank against some of the walls thereof, continued operation of said mechanism turning a portion of each lip turner about the corners of said former while the other portions remain at rest, to bend the corner flaps of the blank inwardly against the ends of the former, combined with means to separate said former and 115 lip turners while the latter remain folded, whereby the bent blank is withdrawn therefrom, substantially as described. 110

4. A reciprocating former, means to move it, and a follower to clamp a blank upon the former, combined with compound lip turners supported adjacent to the path of movement of the corners of said former, and actuating mechanism to move said lip turners against projecting portions of said clamped blank 125 and turn them over upon the former, a portion of the lip turners being turned about the corners and toward the ends of the former, to turn the corner flaps of the blank upon the ends thereof, substantially as described. 130

5. The combination, with a former, compound lip turners pivotally supported adjacent the corners thereof, rock-shafts to which portions of said lip turners are connected,

and means to normally maintain the parts of the lip turners extended, of means to actuate said rock-shafts to move the extended lip turners toward the former, continued movement of said shafts turning the connected portions of the lip turners around the corners of said former, substantially as described.

6. In a box making machine, a former, compound lip turners adjacent the corners thereof, rock-shafts parallel to the sides of the former and extended loosely through hubs on portions of the lip turners, pivotal connections between the parts of each lip turner, and gearing intermediate said rock-shafts and other portions of the lip turners, combined with means to actuate the rock-shafts and thereby move the lip turners bodily toward the former, and thereafter to move portions of them about the corners and upon the ends 20 of the former, substantially as described.

7. In a box making machine, a former, lip turners located adjacent the corners thereof and each consisting of wings or plates hinged together, and rock-shafts on which the lip 25 turners are loosely supported, combined with engaging gears secured upon said shafts and to one wing or plate of each lip turner respectively, means to normally extend the parts of the lip turners, and actuating mechanism for the rock-shafts, to move the lip turners around the said shafts and also to move one plate or wing of each lip turner relatively to its fellow, substantially as described.

30 8. The combination, with a former, of rock-shafts parallel to the sides thereof, folding lip turners provided with hubs loosely embracing said shafts, whereby they are adapted to be adjusted longitudinally thereon, independent 40 of clamps to prevent longitudinal movement of the lip turners on the shafts, connections between the rock-shafts and a portion of each folding lip turner, and means to actuate the rock-shafts and the said former, substantially as described.

45 9. In a box making machine, a reciprocating former, and means to move it, a movable follower to co-operate therewith to clamp a blank, and end and side wiper plates, combined with 50 compound lip turners supported by the side wiper plates and adjustable with relation thereto, and mechanism to actuate the lip turners to move them toward the sides of the former, portions of the lip turners being 55 turned about the corners of and toward the ends of the former, whereby the sides and corner flaps of the blank are turned over and shaped upon the former, substantially as described.

60 10. The combination with the former, rock-shafts, bearings at the extremities of said rock-shafts, compound lip turners provided with hubs loosely embracing said shafts, and adjustable laterally thereon inside of said bearings for boxes of different size, and independent clamps on said shafts to hold said lip turners from longitudinal movement thereon, of

connections between a part of each lip turner and said shafts, and mechanism to positively actuate said rock-shafts and cause the lip-turners to bend successively the sides and corner flaps of the blank about the former, substantially as described.

11. In a box making machine, the former, means to move it, a movable follower, and adjustable side wiper plates parallel to the sides of and adjacent the path of movement of the former, combined with rock-shafts supported at their extremities in bearings on the side wiper plates, compound folding lip turners 80 pivotally supported on said shafts, connections between said shafts and portions of the lip turners, and means to actuate said rock-shafts, whereby the lip turners are moved bodily toward the sides of the former and a portion of each lip turner is thereafter folded about the corners thereof, substantially as described.

12. In a box making machine, a reciprocating former and means to move it, and a movable follower, combined with compound lip turners to turn the side flanges of a blank over upon the sides of the former, portions of each of said lip turners being thereafter moved with relation to the remaining portions to turn 95 the corner flaps of the blank over upon the ends of the former, and end wiper plates to turn the end flaps of the blank down upon the corner flaps as the former is moved between said wiper plates, substantially as described.

13. A stationary central track, laterally adjustable side tracks, guides, auxiliary tracks thereon beyond the side tracks, and means to adjust said auxiliary tracks upon the guides, 105 and cross shafts provided with right and left hand threads to engage bearings in the guides, combined with a connecting shaft, and gearing whereby the said guides are made adjustable simultaneously, substantially as described.

14. An adjustable side guide, a longitudinally adjustable block thereon, and a gage carrier pivoted to said block at the inner side of the guide, and means to turn said gage carrier on its pivot and maintain it in adjusted position, substantially as described.

15. In a box making machine, a former, adjustable pasting devices for the blank located at a distance from the former, a central track 120 and outer tracks intermediate the said devices and said former to sustain the blank while being fed, and adjustable yielding track-like supports interposed between the back of the said former and the adjacent ends of the 125 tracks, combined with rigid connections between said pasting devices and the outer tracks, whereby they are made adjustable simultaneously, the said outer tracks being located at the inner sides of and adjacent said 130 pasting devices, substantially as described.

16. In a box making machine, a former, and means to feed the blanks thereto, one at a time, combined with tracks upon which the blank

is supported while being fed, and adjustable yielding track-like supports interposed between the back of the said former and the adjacent ends of the tracks, whereby formers of different sizes may be used, substantially as described.

17. In a box making machine, a head, and an end gage vertically adjustable therein, combined with a presser-foot composed of a curved plate secured to the head, and a similarly curved co-operating plate adjustably supported by and longitudinally movable with relation to said head, the longitudinal downturned or separated edges of said plates resting on the upper surface of and maintaining the blank flat and preventing buckling thereof, substantially as described.

18. In a box making machine, a former, and a reciprocating feeder to present the blank thereto, combined with a presser-foot comprising co-operating curved plates, the longitudinal downturned edges thereof being adapted to bear upon the upper surface of the blank and maintain it flat when presented to the former, and a yielding stop secured to the under side of the plate of the presser-foot, nearest the said former to engage the rear edge of the blank as it leaves the presser and prevent its displacement by retrogression of the feeder, substantially as described.

19. In a box making machine, a former, and blank supporting tracks terminating some distance from said former, combined with filling plates at the rear of said former and adjustable toward and from it, and yielding track-like supports carried by the filling plates to sustain the blank between said former and the end of the tracks, substantially as described.

20. In a box making machine, tracks to support a blank, wetting devices to moisten said blank parallel to its front and rear edges, and wetting devices to moisten the blank parallel to its side edges, combined with a yoke, pasting devices laterally adjustable thereon, and a rigid connection between each track and the adjacent pasting and end wetting devices, whereby they are simultaneously movable laterally upon said yoke, substantially as described.

21. In a box making machine, a paste pan, pasters therein, a track movable with said pan, and an end wetter for the blank parallel to said track, combined with a reciprocating spindle 55 extended through the paste pan to actuate the pasters, and a support for the end wetter rigidly connected to the spindle and adapted to move therewith laterally and vertically, substantially as described.

22. In a box making machine, a reciprocating yoke, a slide longitudinally adjustable thereon, and an upright and a spindle secured to said slide, combined with a laterally adjustable paste pan through which the spindle 65 is extended, pasters attached to the spindle and an end wetter supported upon the up-

right parallel to the inner sides of the paste pan, substantially as described.

23. The combination with a reciprocating former, of a follower adapted to be raised thereby, a slide-rod attached to the follower, a cylinder on the upper end of the rod, a piston movable therein, and its attached piston rod, and a latch to maintain the piston-rod, elevated, substantially as described. 75

24. In a box making machine, a former, a follower movable thereby, a slide-rod detachably secured thereto, and a cushioning device for the follower, combined with means to normally limit the descent of the follower, and a latch to permit the follower to drop into abnormal position to enable it to be detached from the slide-rod, substantially as described.

25. The combination with a reciprocating former, and means to move it, of a movable follower, a cushioning device therefor, including a cylinder and piston-rod to control the descent of the follower, and a latch for said rod, substantially as described. 85

26. In a box making machine, the threaded pressure screws, and the pressure head, combined with sleeves loosely mounted and rotatable in the said pressure head, substantially as described.

27. In a box making machine, the threaded pressure screws, and the pressure head, combined with sleeves loosely mounted and rotatable in the said pressure head, and with a rack and gearing to oscillate the said pressure screws, substantially as described. 95

28. The pressure head, and the sleeves loosely mounted thereon and provided with pinions, and the threaded pressure shafts, combined with the intermediate gears, substantially as described. 105

29. The pressure head, and the sleeves loosely mounted thereon and provided with pinions, and the threaded pressure shafts, combined with the intermediate gears, and with the worm gear and worm shaft to actuate one of the said intermediate gears, substantially as described. 110

30. In a box making machine, the threaded pressure screws, the pressure head, and sleeves loosely mounted and rotatable in the said head, combined with an end wiper plate supported by and adapted to rock with relation to the pressure head, and yielding supports to act upon the end wiper plate and maintain it in normal position, substantially as described. 115 120

31. In a box making machine, the pressure screws, and the pressure head, combined with sleeves loosely mounted and rotatable in the said pressure head, a rocking block 125 having a convex back to rest in a concavity in the head, an end wiper plate attached to said block, and a yielding support at each side of the concavity to bear against the back of said block, substantially as described. 130

32. The pressure head having a vertical concavity therein, a rocking block having a con-

vex back to rest in the concavity, and an attached end wiper plate, combined with yielding supports adapted to bear upon the back of the block at opposite sides of its center, 5 and adjustable sleeves for the supports, substantially as described.

33. The pressure head, a rigid lug at the bottom and a movable locking lug at the top thereof, and a concavity in the head between them, combined with a convexed-back rocking-block to rest in said concavity, pivots secured to said block and held in place in said lugs, yielding supports between the pressure head and the block at opposite sides of its center, 15 and the end wiper plate attached to the face of the block, substantially as described.

34. The pressure head, a rocking block pivoted thereon, an end wiper plate attached to the face of said block, and a locking device to hold said block in place, combined with spring supported shanks adapted to bear against

the said block and position it and the attached wiper plate, substantially as described.

35. The pressure head having a projecting lug at the top and bottom thereof and a concavity between them, one of said lugs being fixed and the other movable, combined with a rocking block having a convex back to rest in said concavity, a pivot secured to said block and located at the center of the curve forming the convex back thereof, and pivoted in said lugs, means to lock the movable lug in position and thereby retain the block in place, and the end wiper plate attached to the face of said block, substantially as described. 35

In testimony whereof I have signed my name to this specification in the presence of two subscribing witnesses.
